UNITED STATES PATENT OFFICE.

HERMAN A. DAVENPORT, OF BROCKTON, MASSACHUSETTS, ASSIGNOR TO UNITED SHOE MACHINERY CORPORATION, OF PATERSON, NEW JERSEY, A CORPORATION OF NEW JERSEY.

METHOD AND MEANS FOR SHAPING THE BOTTOMS OF SHOES.

Application filed April 26, 1927. Serial No. 186,737.

This invention relates to the shaping of the bottoms of shoes, and in some of its important aspects has more particular reference to the shaping of the shank portion 5 of the sole. While in its more general aspects the invention is not limited in respect to the shape imparted to the sole, it is regarded as of particular utility in the manufacture of shoes of a type in which the sole 10 of the finished shoe has one or more pronounced lines or ridges on its bottom face, such, for example, as shoes the soles of which are shaped to produce what are commonly termed cottage shanks. It is a characteristic 15 of this type of shank that the bottom face of the sole presents one or more well-defined lines or ridges extending lengthwise of the shank, and usually also one or more lines or ridges extending widthwise of the 20 sole at the junction of the forepart and the shank.

In the manufacture of shoes in which the sole thus has on its bottom face one or more pronounced lines or ridges, for example in 25 the shank, at the junction of the forepart and the shank, or in both these locations, it has been the general practice heretofore to shape the sole to the required contour by a molding operation before the sole is assembled 30 with other shoe materials on the last. It is an object of this invention to eliminate the necessity for such a preliminary molding operation in the shaping of a sole of this type. In one important aspect 35 the invention accordingly provides a novel method which consists in applying rolling pressure to level a previously unmolded sole after its assembly with the upper, and interposing between the leveling roll and a portion 40 of the sole a form of substantially unyielding material having a contour substantially complementary to the desired ridged formation of the sole to produce the required ridge or ridges on the bottom of the 45 sole as an incident to the leveling operation. Even when the sole is molded in a separate operation, it requires more or less leveling pressure to correct such deformation as unavoidably results from later operations thereon, such as the rounding, channel-opening 50 and sewing operations, and in accordance with this invention the leveling operation is availed of to produce also the results here-

tofore produced by preliminary molding of the sole.

In another aspect, the invention provides novel means for accomplishing the objects in view, including a form of substantially unyielding material and of the required contour for transmitting the pressure of a leveling roll to that portion of the sole on or adjacent to which one or more well-defined ridges are to be produced. It has been found that such a form may satisfactorily be made of hard leather, such as sole leather, molded 60 in the required shape, although the invention is not limited to that particular material. Such a form may be conveniently attached to a flexible saddle such as used heretofore between a leveling roll and the sole of 65 the shoe, which may be either a saddle of that type which covers mainly the shank portion of the sole or one of the type that covers both the shank and the forepart. It has been found that it assists materially in 70 producing a well-defined line or ridge on the sole to provide in the sole-engaging face of the form a channel located opposite to the required ridge, and sole-shaping means including a form of that character accordingly 75 constitutes a further feature of the invention.

The invention will now be more particularly described by reference to the accompanying drawings and pointed out in the 80 claims.

In the drawings,

Fig. 1 is a view in side elevation of a portion of a leveling machine of the roll type adapted for use to accomplish the objects of this invention;

Fig. 2 is a perspective view of a form adapted to be interposed between the leveling roll and the shank portion of a sole to shape the sole to the contour of a cottage shank, the form being shown as attached 95 to a saddle of the type illustrated in Fig. 1;

Fig. 3 is a cross-sectional view illustrating the shaping of the shank portion of the sole;

Fig. 4 is a view similar to a portion of Fig. 1, illustrating the use of a saddle of a different type from that shown in Fig. 1;

Fig. 5 is a perspective view of the saddle illustrated in Fig. 4; showing a form like 105 that of Fig. 2 attached thereto; and

Fig. 6 is a perspective view of one type of shoe as it appears after the sole has been operated upon in accordance with this invention.

5 For performing what is known as the leveling operation on welt shoes, and sometimes also on shoes of other kinds, it is the common practice to use a machine for subjecting the soles progressively to rolling 10 pressure while the shoes are on their lasts. Such machines are shown and described in detail in various Letters Patent of the United States, including Letters Patent No. 1,239,664, granted on September 11, 1917, 15 upon an application of William C. Baxter. In such a machine the shoe is supported on a jack comprising a heel post 10 and a toe support 12, and the jack is oscillated about a pivot 14 to carry the shoe lengthwise 20 back and forth under a spring-pressed leveling roll 16 carried by an arm 18, the arm being so controlled as to tip the roll about an axis extending lengthwise of the shoe in time relation to the movements of the jack 25 and thus to position it for operating in the desired manner on different portions of the sole. To assist in holding the shoe on the jack and in leveling the sole, there is frequently used a saddle 20 (Fig. 1) made of 30 flexible leather and connected at its opposite sides by springs 22 to a hand lever 24 which is utilized to apply the saddle tightly over the bottom of the shoe. Such a saddle is especially desirable at the shank portion 35 of the shoe, and may extend rearwardly over the heel seat, as illustrated. Alternatively, where the character of the work renders it desirable, there may be used a saddle so formed as to extend also over the forepart 40 of the shoe, as shown at 26 (Figs. 4 and 5), such a saddle being described and claimed in Letters Patent No. 1,644,971, granted on October 11, 1927 upon an application of myself and E. E. Winkley. For holding 45 the full-length saddle in place there are provided additional springs 28 connected to the forepart portion of the saddle.

In the manufacture of some styles of shoes it is customary to shape the shank portion 50 of the sole in such a way as to produce what is termed a cottage shank. It is a characteristic of that type of shank that the sole has on its bottom face one or more well-defined lines or ridges extending lengthwise of the shank, and usually also one or more lines 55 or ridges at the junction of the forepart and the shank, as illustrated, for example, in Fig. 6. In the shoe there shown the opposite side portions of the sole *a* slope laterally in the shank from a central peak line or ridge *b*, while at the junction of the forepart and the shank there are pronounced lines or ridges *c* in angular relation to each other. It has 60 been the general practice heretofore to produce a shank of that kind by molding the

sole separately before it is assembled with the upper on the last. In accordance with this invention, in one of its aspects, the required shaping or molding effect is obtained after the sole has been assembled with the 70 upper, by the use of a roll which, as herein illustrated, subjects the sole to leveling pressure. To this end there is provided a form 30 for engaging the shank portion of the sole to transmit the pressure of the leveling roll 16 thereto, the form having a contour substantially complementary to that of the desired cottage shank and being made of substantially unyielding material so as to hold 75 its shape and to serve effectively as a mold or matrix. The invention is not limited to the use of a form of any particular material, but heavy sole leather molded in the required shape has been found satisfactory. To hold the form in the proper location on the shoe, it may conveniently be attached in any suitable way to a saddle 20 of the short type (Figs. 1 and 2) or to a saddle 26 of the full-length type (Figs. 4 and 5). With the saddle and the form in place on the sole, the leveling roll is made to act in the usual manner over the shank and the forepart, and its pressure in the shank results in imparting to the tempered sole a shape substantially 80 complementary to that of the form 30, as illustrated in Fig. 3. It has been found that it assists in obtaining a sharply defined peak line *b* on the shank to provide the form 30 with a narrow channel 32 extending 85 lengthwise thereof in a location opposite to the peak line, so that the form is substantially out of contact with the sole along that line, at least when the molding pressure begins, the channel serving as a recess into which some of the material of the sole may 90 flow in response to pressure applied in locations adjacent thereto. It will furthermore be observed that the form has an abrupt front edge 34 so disposed as to lie at the junction of the shank and the forepart 95 of the sole, this edge having a contour conformable to the contour of the desired line or ridge in that location on the sole, so that under pressure of the roll the form will produce such a ridge.

100 While the invention is herein illustrated in its application to the manufacture of welt shoes, it is not necessarily limited to the manufacture of shoes of that particular type, since it is contemplated that it may be utilized with advantage in the making of other kinds of shoes. It is further to be understood that the invention is not restricted to the production of shoes having their soles formed with lines or ridges of the precise 105 character herein illustrated.

110 Having described the invention, what I claim as new and desire to secure by Letters Patent of the United States is:

115 1. That improvement in methods of shap- 120

- ing the bottoms of shoes of a type having one or more well-defined ridges on the bottom face of the sole, which consists in applying rolling pressure to a previously unmolded sole on the bottom of a shoe to level the sole, and by interposing between the leveling roll and a portion of the sole a form of substantially unyielding material having a contour substantially complementary to the desired ridged formation of the sole producing the required ridge or ridges on the bottom of the sole as an incident to the leveling operation.
2. That improvement in methods of shaping the bottoms of shoes of a type having a cottage shank, which consists in applying rolling pressure to level the bottom of a shoe having a sole as yet unmolded in cottage shank formation, and by interposing between the leveling roll and the shank portion of the sole a form of substantially unyielding material having a contour substantially complementary to that of a cottage shank producing the desired cottage shank formation on the sole as an incident to the leveling operation.
3. That improvement in methods of shaping the bottoms of shoes of a type having a well-defined ridge at the junction of the forepart and the shank, which consists in applying rolling pressure to level the bottom of a shoe having a sole as yet unmolded in ridged formation, and by interposing between the leveling roll and the shank portion of the sole a form of substantially unyielding material having an abrupt edge at the junction of the forepart and the shank producing the desired ridge on the sole as an incident to the leveling operation.
4. That improvement in methods of shaping the bottoms of shoes to produce one or more well-defined ridges on the bottom face of the sole of the shoe, which consists in applying to the bottom of an unmolded sole, after it has been assembled with the upper, a form of substantially unyielding material having a contour such as to shape the sole with the required ridge or ridges thereon by pressure against it, and applying rolling pressure to said form to shape the sole.
5. That improvement in methods of shaping the bottoms of shoes to produce cottage shanks, which consists in applying to the shank portion of a sole as yet unmolded in cottage shank formation, after the sole has been assembled with the upper, a form of substantially unyielding material having a contour substantially complementary to that of a cottage shank, and applying rolling pressure to said form to shape the sole.
6. A machine for shaping the bottoms of shoes having, in combination, a shoe support and a leveling roll relatively movable to level the sole of a shoe on said support, and means constructed and arranged to co-
- operate with said roll to produce one or more well-defined ridges on the bottom face of a previously unmolded sole in the leveling operation, said means comprising a form of substantially unyielding material having a contour substantially complementary to the desired ridged formation of the sole for transmitting the pressure of the roll to a portion of the sole.
7. A machine for shaping the bottoms of shoes having, in combination, a shoe support and a leveling roll relatively movable to level the sole of a shoe on said support, and means constructed and arranged to co-operate with said roll to produce a cottage shank in a sole previously unmolded in cottage shank formation, said means comprising a form of substantially unyielding material having a contour substantially complementary to that of the desired cottage shank for transmitting the pressure of the roll to the shank portion of the sole.
8. A machine for shaping the bottoms of shoes having, in combination, a shoe support and a leveling roll relatively movable to level the forepart and shank of the sole of a shoe on said support, and a form of substantially unyielding material for transmitting the pressure of the roll to the shank portion of the sole, said form having an abrupt edge arranged to lie at the junction of the forepart and the shank to produce by the leveling pressure a ridge extending widthwise of a sole previously unmolded in ridged formation.
9. A machine for shaping the bottoms of shoes having, in combination, a shoe support and a roll relatively movable to apply leveling pressure to the sole of a shoe on the support, and a saddle of flexible material adapted to be applied between the roll and the shoe bottom and of such length as to extend over the forepart and the shank of the sole, said saddle having secured thereto a form of substantially unyielding material in position to engage the shank portion of the sole and having a contour substantially complementary to that of a cottage shank.
10. A machine for shaping the bottoms of shoes having, in combination, a shoe support and a roll relatively movable to shape the sole of a shoe on said support, and a form of hard leather molded to a contour substantially complementary to that of a cottage shank for transmitting the pressure of said roll to the shank portion of the sole.
11. In a machine of the class described, the combination with a shoe support and a roll relatively movable to shape the sole of a shoe on said support, of a form for transmitting the pressure of the roll to a portion of the sole, said form having different portions of its sole-engaging face meeting at an angle and having a channel in said face at the vertex of said angle.

12. In a machine of the class described, the combination with a shoe support and a roll relatively movable to shape the sole of a shoe on said support, of a form for transmitting the pressure of the roll to the shank
- 5 portion of the sole, said form having a contour substantially complemental to that of

a cottage shank and having in its sole-engaging face a channel so arranged as to be located opposite to the peak of the cottage shank. 10

In testimony whereof I have signed my name to this specification.

HERMAN A. DAVENPORT.
